UNITED STATES PATENT OFFICE.

FRED ROEGER, OF HASBROUCK HEIGHTS, NEW JERSEY, ASSIGNOR OF ONE-HALF TO
HOWARD S. NEIMAN, OF NEW YORK, N. Y.

MEMORANDUM-PAD DEVICE.

Application filed April 3, 1926. Serial No. 99,451.

My invention relates to memorandum pad devices and refers particularly to devices of this character in which the used sheets may be retained for future reference.

5 My device presents a means whereby the upper, or used sheets of a pad of paper sheets can be transferred from the top of the pad to the bottom thereof, the plurality of sheets being retained in locked position 10 with respect to each during the process of sheet transference.

There are evident advantages in a device of the described description among which are the ability to use both sides of the sheet 15 for memorandum purposes, the impossibility of the sheets becoming disarranged, the retention of a used sheet for future reference, the presentation of an unused top sheet and the possibility of removing any particular 20 sheet for reference purposes.

Among the advantages of the device of my invention are ease of insertion of a new pad, the possibility of reversing the entire pad when one side of each sheet has served 25 its purpose, the stability of the device and the ease of packing the sheets properly upon each other to form an attractive and useful memorandum pad.

These and other advantages of the device 30 of my invention will be evident upon a consideration of my specification and accompanying drawings.

In the accompanying drawings illustrating modified forms of the device of my invention similar parts are designated by similar numerals.

Figure 1 is a perspective view of one form of the device of my invention.

Figure 2 is a cross-section through the 40 line 2-2 of Figure 1.

Figure 3 is a cross-section through the line 3-3 of Figure 4.

Figure 4 is a vertical cross-section of a portion of a modified form of my device 45 showing means for the attachment of the frame member to the hinge member.

Figure 5 is a perspective view of a clip employed for the retention of the loose ends of the sheets of a pad in fixed position.

50 Figure 6 is a perspective view of a pad of sheets of paper suitable for insertion in the frame member of my device.

Figure 7 is a perspective view of a modified form of frame.

55 Figures 8 and 9 illustrate the method of

sheet transference from the top to the bottom of the pad.

Figure 10 is a perspective view of one form of link connecting means.

Figure 11 is a perspective view of a portion of a modified form of frame member.

The particular form of the device of my invention shown in Figures 1 and 2 comprises a book-like hinged cover having the bottom member 12 and the top, or cover, 65

member 13 both hingedly attached to the back, 14.

A sheet of cloth, leather, or other suitable material 15 covers the outer faces of the members 12, 13 and 14 and is attached thereto.

A sheet of cloth, leather, or other suitable material 16 covers the inner face of the cover 13 and is attached thereto, then passes downwardly within the back 14, but is not attached thereto, and then extends

across the inner face of the member 15 and 75

is attached thereto. The sheets 15 and 16 are sewed together at the jointure line 17

of the members 13 and 14 and at the jointure line 18 of the members, 14 and 12,

thus forming hinges. A closed frame 19 of 80

stiff material as metal, cardboard, etc. is positioned in the opening between the back 14

and the sheet member 16 before the latter is attached to 15, the frame 19 thus being capable of pivotal movement to allow it to be 85

placed in edge abutment with either of the inner faces of the bottom and cover or in

abutment with both.

Within the frame 19 is a plurality of 90

superimposed sheets of paper 20, affixed to the frame 19 by means of two separable

links each composed of the two telescopic members 21 and 22, the link members 22, 22

passing through openings in the sheets of 95

paper.

For purposes of convenience of operation, the pad of paper sheets has a cut-out 23, and in order that the bottom 12 and cover 13 may be in parallel position when the book is closed, recesses 24, 24 are made in 100

the cover 13, and recesses 25, 25 are made in

the bottom 12 to receive the binding

links 21, 22.

The operation of the device is as fol-

lows:—

When the top sheet of paper has served its purpose and it is desirous of exposing the next under-lying sheet, the book is opened as shown in Figure 8, the top sheet 20 is moved in the direction of the arrows 110

and in the position 20^a, 20^b and 20^c. The frame 19 is then raised to a vertical position as shown in Figure 9, the sheet allowed to fall as 20^d until it is in abutment with the bottom sheet and the frame 19 is then returned to the position 19^a. The pad of paper is then positioned as shown in Figure 1, the top sheet having been positioned at the bottom of the sheets and a new one ¹⁰ exposed for use.

In the modification of my device shown in Figures 3, 4 and 5, the frame 19 is riveted to the back 14 by means of the two rivets 26, 26 and a loose clip 27, 28, 29 is slipped ¹⁵ over the loose end of the pad of paper sheets, the cut-out, or recess 23 being eliminated. The clip serves to keep the plurality of sheets in edge alignment. The operation of this device is similar to that described above, ²⁰ except, as shown in Figure 9, the sheet 20^d is inserted behind the clip to retain it in position.

In the modification of the frame shown in Figure 7, the member 27^a integral with ²⁵ the frame serves the same purpose as the member 27 of the clip shown in Figure 5.

Figure 6 illustrates a pad of sheets of paper 20, capable of being inserted in the frame 19 and having the holes 30, 30 for the ³⁰ insertion of the binding, or connecting links 21, 22. The paper strips 31, 31 retain the plurality of sheets in proper condition and position with respect to each other.

When the pad of paper sheets has served ³⁵ its purpose, the links 21, 22 are opened, the pad removed from the frame 19, and a new pad is introduced and the links inserted.

Figure 11 illustrates a modified form of frame 19, in which the top and bottom edges ⁴⁰ 32, 32 are turned over upon themselves to form a strengthening means for the frame, thus allowing of thinner material for its formation.

It is evident that the cover 16 may be ⁴⁵ omitted without interfering with the device of my invention, and that the holes 30, 30 may vary in number and position within the paper sheets.

It will be seen from the above that a pad ⁵⁰ of paper sheets, such as shown in Figure 6 can be readily placed within the frame 19 and attached thereto by the links 21, 22. That when so positioned, the upper exposed sheet after service may be placed at the bottom of the pad thus exposing the next successive sheet. When all of the sheets of ⁵⁵ the pad have been used, the pad may be taken from the frame and re-placed therein in reversed position, thus exposing the unused sides of the sheets for service.

The sides of the frame 19 are of a material possessing sufficient rigidity to support the pad during the transference of a sheet of paper from the top to the bottom of the ⁶⁰ pad, and it is to material having such char-

acteristics that I refer to it by the word "rigidity" or "rigid" in my specification and claims.

I do not limit myself to the particular size, shape, number, arrangement or material of parts as shown and described as these are given simply for the purpose of clearly describing my invention.

What I claim is:

1. In a memorandum pad device in combination, a base, a member perpendicular to the base and hingedly carried thereby, a rigid frame carried by the perpendicular member capable of extending around the edges of a plurality of paper sheets and a plurality of separable rings capable of passing through a plurality of holes in the paper sheets within the frame.

2. In a memorandum pad device, in combination; a base; a member perpendicular to the base and hingedly carried thereby; a rigid frame fixedly attached to the perpendicular member; a plurality of sheets of paper within the frame, the frame extending around the edges of the paper sheets, and a plurality of binding members passing around one of the frame members and through the plurality of sheets whereby the top sheet may be transferred to the bottom of the sheets without separating the sheets from the binding members.

3. In a memorandum pad device, in combination; a base; a member perpendicular to the base and hingedly carried thereby; a rigid frame fixedly attached to the perpendicular member; a plurality of sheets of paper within the frame, the frame extending around the edges of the paper sheets, a plurality of binding members passing around one of the frame members and through the plurality of sheets whereby the top sheet may be transferred to the bottom of the sheets without separating the sheets from the binding members and a separable clip for removably maintaining the free ends of the sheets in pad form.

4. In a memorandum pad device, in combination; a base; a member perpendicular to the base and hingedly carried thereby; a rigid unitary frame fixedly attached to the perpendicular member; a plurality of sheets of paper within the frame, the frame extending around the edges of the paper sheets, and a plurality of binding members passing around one of the frame members and through the plurality of sheets whereby the top sheet may be transferred to the bottom of the sheets without separating the sheets from the binding members.

5. In a memorandum pad device, in combination; a base; a back hingedly attached to the base; a cover hingedly attached to the back; a rigid frame fixedly attached to the back; a plurality of sheets of paper within the frame, the frame extending

around the edges of the paper sheets and a plurality of binding members passing around one of the frame members and through the plurality of sheets whereby the 5 top sheet may be transferred to the bottom of the sheets without separating the sheets from the binding members.

6. In a memorandum pad device, in combination; a base; a back hingedly attached 10 to the bottom; a cover hingedly attached to the back; a rigid frame fixedly attached to the back; a plurality of sheets of paper within the frame, the frame extending around the edges of the paper sheets, a plurality 15 of binding members passing around one of the frame members and through the plurality of sheets whereby the top sheet may be transferred to the bottom of the sheets without separating the sheets from 20 the binding members and depressions with-

in the bottom and cover for the accommodation of the binding means.

7. In a memorandum pad device, in combination; a base; a back hingedly attached to the bottom; a cover hingedly attached to 25 the back; a rigid frame fixedly attached to the back; a plurality of sheets of paper within the frame, the frame extending around the edges of the paper sheets and a plurality of separable links passing around 30 one of the frame members and through the plurality of sheets whereby the top sheet may be transferred to the bottom of the sheets without separating the sheets from the separable links. 35

Signed at New York city in the county of New York and State of New York this 21st day of March, 1926.

FRED ROEGER.
